DES. 2164

Charles T. Foote of Bristol, Conn.

Letters Patent No. 2164. Dated Sept. 12. 1865

Design for a clock Case.

The schedule referred to in these Letters Patent and making part of the same.

To all whom it may concern.

Be it known that

I, Charles T. Foote of Bristol, County of Hartford, and State of Connecticut, have invented or produced a new or original design for a clock base, and do hereby declare that the following is a full, and exact description of the same, referring to the photographic views in which the same letters indicate like parts.

In the accompanying photographic views are shown a new and original Design for a clock base. A is a plain and slightly diverging base having its upper edge molded with an oval. B are plain sides with oval edges. C, is a square plain edge cap. D is a plain oval ornamental mold. E is a plain Ogee lash. The whole combined to form a plain ornamental design for a Clock base.

That I claim therefore and desire to secure by Letters Patent is the design for a clock case as herein above illustrated and set forth:
